E. L. PEMBERTON.
TOOTH FOR EXCAVATING BUCKETS.
APPLICATION FILED JAN. 18, 1911.

995,285.

Patented June 13, 1911.

UNITED STATES PATENT OFFICE

EDWARD LOUIS PEMBERTON, OF NEW HAVEN, CONNECTICUT.

TOOTH FOR EXCAVATING-BUCKETS.

995,285.

Specification of Letters Patent. Patented June 13, 1911.

Application filed January 18, 1911. Serial No. 603,257.

To all whom it may concern:

Be it known that I, EDWARD L. PEMBERTON, a citizen of the United States, and a resident of New Haven, in the county of 5 New Haven and State of Connecticut, have invented a new and Improved Tooth for Excavating-Buckets, of which the following is a full, clear, and exact description.

My invention relates to improvements in 10 teeth for excavating buckets, and it has for its object to provide one having a detachable point, so secured to the body of the tooth that it may be reversed when desired. In practice the points of these teeth usually be- 15 come worn on the lower cutting surface, and it is my purpose to provide a tooth with a reversible point so that great additional wear may be obtained.

Additional objects of the invention will 20 appear in the following complete specification, in which the preferred form of my invention is described.

In the drawings similar characters of reference indicate corresponding parts in all 25 the views in which:

Figure 1 is a perspective view showing a bucket provided with my improved tooth; Fig. 2 is an enlarged sectional view showing my improved tooth; Fig. 3 is a plan view of 30 Fig. 2; Fig. 4 is a perspective view showing the point of the tooth member; and Fig. 5 is a perspective view showing the shank of the tooth member.

By referring to the drawings it will be 35 seen that a shank member 5 is provided, having a slot 6, in which the edge of the bottom 7 of the bucket 8 is normally disposed. There are rivet orifices 9 in the shank 5 by which means the shank may be riveted to the bot- 40 tom portion 7 of the bucket. The forward end of the shank member 5 is provided with two projections 10, these projections being spaced apart at the sides of the shank mem- ber. The upper and lower edges of the pro- 45 jections 10 are connected together by mem- bers 11, the upper member 11 extending above the upper plane of the projections 10, and the lower member 11 extending below the lower plane of the projections. An 50 elongated recess 13 is connected with the opening 12 between the projections 10, and a rivet orifice 14 extends through the shank member 5, and connects with the elongated recess 13. The point member 15 has a 55 tongue 16, which is adapted to be disposed

in the opening 12 between the projections 10, and to extend in the elongated recess 13, there being a rivet opening 17 in the terminal 16 which is normally disposed in alignment with the opening 14. The upper and 60 lower members of the point member 15 are continued to form flanges 18, which are normally disposed against the upper and lower portions of the projections 10, there being recesses 19 in the flanges 18 for receiving the 65 members 11. Lateral openings 20 are made in the point members 15, which are disposed slightly in advance of the ends of the projections 10, when the point member 15 is secured to the shank member 5, as shown in 70 Fig. 2 of the drawings.

In using the invention the point member is disposed with its tongue 16 in the elongated recess 13, a rivet 21 being provided which extends through the opening 14 and 75 the opening 17 to hold the point member firmly in place. When the point member 15 is disposed in place it will be seen that it will be rigid on the shank member 5, since not only will the tongue 16 serve to so hold 80 it, but the flanges 18 with their recesses 19 will engage the upper and lower portions of the shank member to prevent any possible displacement. But not only will the point member 15 be held rigidly on the 85 shank member 5, by the features described, but it will be seen that when the rivet 21 is withdrawn, a pin may be inserted in the openings 20, and pried against the ends of the projections 10, by which means the point 90 member 15 may be freed from the shank member 5. When this has been done, the point member 15 may be reversed, and may again be secured to the shank member 5 in the manner which has been described. 95 The point member may be reversed several times until it is worn out, when it may be replaced by a new point member.

Having thus described my invention, I claim as new and desire to secure by Let- 100 ters Patent:

1. In a tooth for excavating buckets a member having two projections with sides spaced apart, a tooth member having a pro- 105 jection normally disposed between the sides of the first-mentioned projections, and flanges on the tooth member disposed against opposite edges of the said first-mentioned projections, there being an opening in a side of the tooth member in which a pin may 110

be disposed for engaging one of the projections for prying the tooth member from the first-mentioned member.

2. In a tooth for excavating buckets a member having two projections spaced apart, members connecting opposite edges of the projections and extending therebeyond, a tooth member having a tongue disposed between the projections, and flanges disposed against opposite edges of the projections, there being recesses for receiving the second-mentioned members.

3. In a tooth for excavating buckets a member having two projections spaced apart, members connecting opposite edges of the projections and extending therebeyond, a tooth member having a tongue disposed between the projections, flanges disposed against opposite edges of the projections, there being recesses for receiving the second-mentioned members, there being an opening in a side of the tooth member in which a pin may be disposed for engaging one of the projections for prying the tooth member from the first-mentioned member.

4. In a tooth for excavating buckets a member having two projections spaced apart, members connecting opposite edges of the projections and extending therebeyond, there being a recess in the member connected with the opening between the flanges, and an opening extending to the recess, a tooth member having a tongue disposed between the projections and extend-

ing in the recess, there being an opening in 35 the tongue normally disposed in alinement with the first-mentioned opening, and flanges disposed against opposite edges of the said projections, there being recesses in the flanges for receiving the second-mentioned members. 40

5. In a tooth for excavating buckets a member having two projections spaced apart, members connecting opposite edges of the projections and extending therebeyond, there being a recess in the member 45 connected with the opening between the flanges, and an opening in the member extending to the recess, a tooth member having a tongue disposed between the projections and extending in the recess, there being an opening in the tongue normally disposed in alinement with the first-mentioned opening, flanges on the tooth member disposed against opposite edges of the said projections, and having recesses for receiving the second-mentioned members, there being an opening in a side of the tooth member in which a pin may be disposed for engaging one of the projections for prying the tooth member from the first-mentioned member. 55

In testimony whereof I have signed my name to this specification in the presence of two subscribing witnesses.

EDWARD LOUIS PEMBERTON.
